CLAIM

The ornamental design for a pet food dispenser, as shown and described.

DESCRIPTION

FIG. 1 is a front elevation view of a pet food dispenser showing my new design, each of a rear side, a right side, and a left side thereof being a mirror image of the shown; FIG. 2 is a top plan view thereof;

FIG. 3 is a bottom plan view thereof;

FIG. 4 is a right isometric view thereof; and,

FIG. 5 is a left isometric view thereof.

The broken lines in FIG. 4 of the drawings depict a pet bowl and dry pet food and in FIG. 5 of the drawings depict water as environmental subject matter only and form no part of the claimed design.
